UNITED STATES PATENT OFFICE

2,196,893

WEFT STRAIGHTENING APPARATUS

Theodore M. Berry, Schenectady, N. Y., assignor
to General Electric Company, a corporation of
New York

Application August 27, 1938, Serial No. 227,148

12 Claims. (Cl. 26—51)

My invention relates to the manufacture of woven material, such as woven fabrics, where it is desirable that the finished material shall be straight, that is, that there shall not be any skew or bow in the weft elements thereof.

The object of my invention is to provide improved apparatus for straightening woven material whether the lack of straightness therein is due to the material being either skewed or bowed or being both skewed and bowed and whether the lack of straightness exists throughout the entire width of the material or is present in only a certain portion thereof.

My invention will be better understood from the following description taken in connection with the accompanying drawings and its scope will be pointed out in the appended claims.

Referring to the drawings, Fig. 1 is a perspective view of apparatus embodying my invention; Fig. 2 is a detail of a portion thereof; Fig. 3 shows one of the optical systems forming a part thereof; Fig. 4 shows a portion of the material requiring straightening together with a part of the one optical system; and Fig. 5 is a circuit diagram of the apparatus.

In the drawings the strip of material to be straightened is shown at 1 arranged to be drawn along longitudinally by being wrapped around the roll 2 having driving means, not shown, the strip as it approaches the roll passing over the idler rolls 3 and 4. As the material is drawn along, I project therethrough a transversely moving narrow beam of light which is successively intercepted by the weft members of the material and the resulting interruption of this beam of light by the weft members produces impulses the frequency of which is used to detect any lack of straightness in the weft members, such as may result from the presence of skew or bow in the material, and to control mechanism for correcting such lack of straightness.

For thus projecting the light beam through the material I have provided mechanism similar to that shown in the La Pierre Patent 2,106,611. As shown in Fig. 2, the apparatus comprises the rotatable disc 5 having therein a plurality of equally spaced radial slots 6, the disc being directly mounted on the shaft of the electric motor 7. Adjacent to the motor is the optical system 8 which comprises the light source 9, such as a small electric lamp, the light from which is focussed by the condensing lens 10 and the cylindrical lens 11 into a narrow beam on the disc 5 which disc, it will be understood, is arranged close beneath the strip 1. Above the strip and in alignment with the aforesaid lenses is the condensing lens 12 and the photo-electric device 13, such as for example a photo-electric tube. As shown more clearly in Fig. 4 the narrow light beam represented at 15 by a single black line as seen

through a slot 6 and by dotted lines at each side thereof, extends transversely of the strip and the warp members thereof. As a result of the rotation of the disc 5 and the longitudinal movement of the strip, that portion of the light beam which passes through the successive slots 6 in the disc as it rotates will move in a path relative to the strip which extends diagonally thereof as shown by the dotted rectangle 16. It will readily be seen that if the cloth is straight, that is if the weft members extend at right angles to the warp members, the number of interruptions of the light beam will be of a certain value. If, however, the weft members are inclined in one direction, such for example as shown in Fig. 4, the number of interruptions of the light beam due to the passage of each slot 6 will be decreased. Conversely, if the weft members are inclined in the opposite direction the number of interruptions will be increased. Thus, if the material is straight the frequency output of the photoelectric device 13 will have a certain definite value but if there is skew or bow in the material the frequency of the output will be increased or decreased in accordance with the character of the skew or bow and also the amount of increase or decrease in the frequency will be a measure of the amount of the skew or bow.

To provide a basis of comparison of the variable output frequency of the device 13, I cause the weft elements of the material successively to interrupt another light beam which is stationary. This second light beam is produced by a suitable source such as a small electric lamp 18 whose light is focused by means of the condensing lens 19 and the cylindrical lens 20 into a narrow beam extending transversely of the warp elements of the strip like that produced by the optical system 8. On the opposite side of the strip the light is focused by the condensing lens 21 onto the photoelectric device 22 which may be a photo-electric tube like the device 13. As the strip 1 is drawn along, the output of the device 22 will have a frequency corresponding with the number of weft elements passing a fixed point. By the apparatus to be described later, any lack of straightness in the strip of material is detected by a comparison of the output frequency of the devices 13 and 22. The presence of skew or bow in the strip not only is detected but mechanism for correcting such a condition is controlled.

In accordance with one feature of my invention the optical system 8 is caused to reciprocate back and forth continually across the strip whereby various transverse portions thereof are examined for any lack of straightness. For this purpose I have provided two transversely movable carriages one shown at 24 below the strip arranged to slide on the stationary transverse guides 25 and the other shown at 26 above the strip arranged to slide

on the stationary transverse guides 27. The lower carriage 24 includes the flat plate 28 over which the strip slides and the housing 29 which supports the motor 1 and the optical system 8. 5 The other carriage 26 includes the housing 30 containing the photoelectric device 13 and the housing 31 which contains the amplifier for the photoelectric device. These two carriages are caused to travel back and forth across the strip 10 in unison by means of the two shafts 33 and 34 each having reverse threads or grooves cut there-in which are engaged by followers carried by the respective carriages. The shafts 33 and 34 are geared together by the spur gearing 35 and 15 are arranged to be driven from the drum 2 by means of the countershaft 36 and suitable bevel gearing at the ends thereof. Thus, as the drum rotates to draw along the strip, the two car- 20riages are caused to travel back and forth in unison across the strip with a speed which is proportional to the rate of movement of the strip. While the carriages thus travel across the strip, the apparatus automatically detects any skew or bow that may exist in the strip as a 25 whole or in any local transverse portion thereof.

In accordance with another feature of my in-vention I have provided means automatically to remove any such bow or skew that may be de- 30tected in the strip. I do this by providing means for resisting the forward movement of the strip at the proper transverse portions thereof in ac- 35cordance with the amount of skew or bow to be corrected. Mounted in the upper carriage 21 is the caster 38 having the rubber roller 39 adapted to squeeze the material against the lower plate 28 and having its shank 40 pressed downward by the compression spring 41. The compression of this spring is controlled by the electric motor 42 on whose shaft is the worm 43 engaging the worm 40 wheel 44. This wheel is threaded on the screw 45 engaging the spring and is retained against longitudinal movement in the carriage by the spline and pin connection 46. Thus, if the motor shaft turns in one direction in response to the 45 detection of skew or bow in the material, the spring 41 will be compressed to increase the drag imposed upon the forward movement of the material. Conversely, if the motor shaft turns in the opposite direction, the drag imposed on 50 the material will be decreased or eliminated.

The apparatus by which the frequency output of the two photoelectric devices 13 and 22 are compared, represented diagrammatically by Fig. 5, is like that disclosed by Fig. 6 in the above- 55 mentioned La Pierre Patent 2,106,611 in that I employ a main capacitor 64 which is given a charge of one polarity or the other from the auxiliary capacitors 63 and 65 in accordance with the relative frequency output of the two photo- 60 electric devices. The auxiliary capacitors are kept charged from the source of direct current supply 61. Inasmuch as the apparatus which I employ for thus charging the capacitor 64 and which I have shown in Fig. 5 is identical with 65 that disclosed in the aforesaid patent, I shall omit a detailed description of such apparatus herein. By the apparatus which I shall now describe, the direction of rotation of the motor 42 is con- 70 trolled by the polarity of the charge on the capacitor 64 and the speed of rotation of said motor is controlled by the amount of the charge on said capacitor. The motor is provided with the two opposed field windings 70 and 71 which are included respectively in the anode circuits of 75 the vapor electric discharge devices 72 and 73,

which circuits are supplied with alternating cur- 1 rent from the secondary 74 of the transformer 75, the armature of the motor being connected in series therewith. The primary of the transformer may be supplied from any suitable source. The 2 grid circuits of the discharge devices 72 and 73 are supplied from across the resistors 68, which with the resistor 66 form a voltage divider across the capacitor 64. The grids are also supplied with phase displaced voltage obtained from the 3 secondary winding 76 of transformer 75 through the phase displacing network 77 which is of well known construction.

Preferably the speed of the motor 42 is sub- 4 stantially proportional to the tangent of the 5 angle of inclination of the weft elements of the strip from their normal perpendicular relation. Then since the force tending to retard any por- 6 tion of the strip bears a direct relation to the 7 pressure exerted thereon by the roller, the com- 8 bination of the motion of the roller across the 9 strip and the rotation of the motor 42 will cause 10 a correcting force to be applied to the strip which 11 is proportional to the displacement of the weft 12 elements away from the straight or normal posi- 13 tion thereof.

Referring to Fig. 4, it will be seen that with 14 the material of the strip skewed as therein shown 15 and moving to the right, if the scanning appa- 16 ratus carried by the carriages is moving upward as 17 viewed in that figure, the motor 42 should operate 18 in the direction to increase the pressure ap- 19 plied by the roller 39. Conversely if the scanning 20 apparatus is moving downward, the motor should 21 operate in the direction to decrease the applied 22 pressure. For this reason I reverse the direction 23 of rotation of the motor at each end of the path 24 of travel of the carriages. A reversing switch 25 represented at 80 in the armature circuit of motor 26 42 is supported by the upper housing 31 and is 27 moved to one position or the other by the project- 28 ing arm 81 thereof engaging one or the other of 29 the two fixed stops 82, 83 which are properly 30 positioned with respect to the path of the move- 31 ment of the carriages.

In the operation of the apparatus the strip 1 is drawn along in the direction indicated by the 2 arrow by means of the driving roll 2. Through 3 their connection with the driving roll the two 4 carriages travel simultaneously back and forth 5 across the strip thereby scanning all parts there- 6 of between its two edges. With the strip moving 7 at a constant speed and having straight weft ele- 8 ments and with a constant speed of rotation of 9 the disk 6 the interruption of the light beam of 10 the optical system 8 and hence the output fre- 11 quency of the photo-electric device 13 will have a 12 fixed and definite value. If, however, the strip 13 is skewed or bowed the frequency will be greater 14 or less than before depending upon the direction 15 of the inclination of the weft elements. Also the 16 amount of change in the frequency will depend 17 upon the degree of the inclination. The output 18 frequency of the device 22 remains fixed since 19 it depends only upon the speed of the strip. 20

The apparatus by which the main capacitor 21 is charged from the auxiliary capacitors 63 and 65 is so adjusted that when there is no skew or 22 bow in the strip the net charge on the main 23 capacitor is zero. An inclination however of the 24 weft elements in one direction or the other due 25 to skew or bow causes the main capacitor to 26 receive a charge of one polarity or the other and 27 the amount of such charge is a measure of the 28 amount of the inclination. 29

The motor 42 by which a variable drag is applied to oppose the movement of a portion of the strip is controlled by the discharge devices 72 and 73 in accordance with the charge on the main capacitor. Thus, if the capacitor has a charge of one polarity the device 72 will pass more current than the device 73 and the motor will run in one direction; likewise, if the capacitor charge has the opposite polarity the device 10 73 will pass the more current and the motor will run in the other direction. Moreover, the motor speed in each case will depend upon the amount of the charge on the main capacitor. Since the carriages carrying the scanning apparatus and the motor actuated pressure wheel for straightening the material are carried continually back and forth across the strip it will be seen that by the apparatus which I have devised all portions lying between the two edges or selvages of the strip are scanned and subjected to whatever corrective effect is necessary to remove any skew or bow that may be present therein.

What I claim as new and desire to secure by Letters Patent of the United States is:

25 1. In combination, means for moving a strip of woven material longitudinally and means arranged to cooperate therewith for detecting any lack of straightness in the weft members of said material comprising fixed means for producing 30 impulses in response to the passage thereby of the weft elements of the material, transversely movable means for producing impulses in response to the passage thereby of the weft elements and a device operable in response to a 35 difference in the frequencies of said impulses.

2. In combination, means for moving a strip of woven material longitudinally, fixed means for producing an impulse frequency in response to the passage thereby of the weft elements of the 40 material, means movable transversely of the strip for producing an impulse frequency in response to the passage thereby of said weft elements and means responsive to a difference in 45 said impulse frequencies for straightening the weft elements of said material.

3. In combination, means for moving a strip of woven material longitudinally, means for illuminating portions of said strip, a plurality of photoelectric devices arranged each to receive 50 a narrow beam of light from one of said illuminated portions and rendered pulsating by the weft members of the material, one of said beams being stationary, means for moving the other of said beams transversely of the strip simultaneously with the longitudinal movement thereof and straightening means responsive to a difference in the output frequencies of said devices.

4. In combination, means for moving a strip of woven material longitudinally, means for illuminating said strip, a plurality of photoelectric devices each arranged to receive light in a narrow beam from said strip whereby the passage of the successive weft elements of the material produce impulses in the received light, means for holding one of said devices in a fixed position, 60 means for moving another of said devices transversely of said strip and means movable transversely of the strip for straightening the weft elements thereof in response to a difference in the output frequencies of said devices.

70 5. In combination, means for moving a strip

of woven material longitudinally, means for detecting a lack of straightness in the weft elements of said material successively at various different transverse portions thereof and straightening means for said elements operable with a variable effect at said portions of the material in accordance with the lack of straightness detected thereat.

6. In combination, means for moving a strip of woven material longitudinally, means movable across said strip for detecting a lack of straightness of the weft elements therein and straightening means for said elements operable with a variable effect at different transverse portions of the strip in accordance with the lack of straightness detected at said portions.

7. In combination, means for moving a strip of woven material longitudinally, means movable across said strip for detecting a lack of straightness of the weft elements thereof and straightening means for said elements movable across said strip and constructed to produce a variable effect at different transverse portions thereof in response to the amount of the detected lack of straightness at said portions.

8. In combination, a drum arranged to engage and move a strip of woven material longitudinally and straightening means therefor comprising means for impeding the longitudinal movement of the strip at one point thereof, means for causing said point to move across the strip and means for varying the effect of said impeding means.

9. In combination, a drum arranged to engage and move a strip of woven material longitudinally and straightening means for the weft elements thereof comprising a plate over which said strip moves, means movable transversely of the strip for pressing a portion of the strip against the plate to impede its movement and means for varying the pressure exerted by said pressing means.

10. In combination, a drum arranged to engage and move a strip of woven material longitudinally and straightening means for the weft elements thereof comprising a plate over which said strip moves, means for moving said plate transversely of the strip and means movable with said plate for variably pressing the material against it.

11. In combination, a drum arranged to engage and move a strip of woven material longitudinally, means for detecting a lack of straightness in the weft elements of the material at a point which moves across the strip, means for impeding the longitudinal movement of the strip at a part thereof adjacent said point and means responsive to said detecting means for varying said impeding means.

12. In combination, a drum arranged to engage and move a strip of woven material longitudinally, means including a photoelectric device movable across said strip for detecting a lack of straightness of the weft elements in the successive transverse portions of the strip, a plate on one side of the strip, a roller on the other side thereof movable with and arranged adjacent to said device and means responsive to said detecting means for variably pressing the strip between the plate and the roller.

THEODORE M. BERRY. 70
